UNITED STATES PATENT OFFICE.

ERWIN KLEIN, OF VOSLAU, NEAR VIENNA, AUSTRIA.

PROCESS FOR DRYING YEAST.

1,420,558.

Specification of Letters Patent. Patented June 20, 1922.

Application filed March 24, 1922. Serial No. 546,502.

To all whom it may concern:

Be it known that I, Dr. ERWIN KLEIN, chemical engineer, a subject of the Kingdom of Roumania, residing at Voslau, near Vienna, in the Republic of Austria, have invented new and useful Improvements in a Process for Drying Yeast, of which the following is a specification.

My invention relates to improvements in the manufacture of pressed yeast, especially to improvements in drying such yeast, and consists of an improved method or process for drying pressed yeast in order to insure a more uniformly dried final product which will be in a condition better adapted to be influenced and improved by added substances suitable to enhance the effect of such yeast, than the yeast obtained by the hitherto known drying processes.

The commonly known processes and methods for drying pressed yeast consist in drying yeast by means of air passed through the particles of yeast which are obtained by dividing the yeast by means of oscillating sieves, turning devices of different kinds and other means so as to reduce the yeast into a crumbly or granulated mass. A still finer subdivision of the particles into a pulverized state has not been carried out in order to avoid losses incurred by the flying away of the yeast in the form of dust together with the current of air.

For conserving the energy of the yeast during the drying process, the temperature of the current of air employed for this purpose is not allowed to surpass a certain limit. Generally, this temperature of the current of air used in connection with a crumbly or granulated mass of yeast is not allowed to be higher than 10 to 15 degrees C. in the beginning of the drying process and may be raised to about 30 to 40 degrees C. in the final period thereof. The pressure of such air is about 3 atmospheres.

According to the present invention the process for drying pressed yeast is carried out by means of a current of air of higher temperature and of lower pressure than hitherto employed on account of the yeast being brought into a most finely divided state, preferably in a pulverized or dust-like state.

The fact that the yeast is brought into a

most finely divided state allows of the use of air of low pressure, because a low pressure is sufficient to bring the air into intimate contact with all fine particles of the yeast, whereas with only coarsely divided yeast, the pressure of the current of air must be materially above that of the atmosphere to penetrate into the interior of the relatively large particles of yeast and to dry them.

Furthermore large quantities of air of more elevated temperature may be passed through the yeast owing to its finely divided state on account of the dehydration of the yeast taking place so quickly that the particles of the yeast are not heated to the temperature of the current of air because they are cooled by the losses of heat created by the evaporation of the content of water of the yeast particles.

The use of an elevated temperature of the current of air accelerates the drying process and renders it more economical. Contrary to the known processes in which the subdivision is only carried out to such degree that the yeast particles cannot fly away in the form of dust, the process according to the invention is executed in such a manner that the most feasible quantities of yeast are carried along with the current of air and brought thereby to a collector in which finishing of the drying to the desired content of humidity is effected by means of a still more heated current of air.

The process is preferably carried out in the following manner. After a preliminary coarse subdivision of the yeast it is brought into a closed container having a stirring or cutting device acting to bring the yeast gradually into a most finely divided state. The container is provided with air inlet and outlet ports and is supplied with a current of air of a temperature of about 20 to 30 degrees and having a somewhat elevated pressure. This current of air, which may be dried previously, is passed into the container and through the yeast contained therein until the degree of humidity of the yeast is lowered to about 30%. The current of air is then heated to about 50 degrees C. and regulated in such a manner that the particles of yeast brought to the desired degree of humidity are carried along and supplied to a special container serving to collect the dust.

like particles of yeast. This collector may be provided with heating means thereby rendering possible, if desired, a final drying of the yeast.

- 5 An apparatus suitable to carry out the process above described essentially consists of a container provided with conduits serving for the inlet and outlet of a current of air and with an intermediate partition-bottom 10 having apertures; the yeast is deposited on this partition-bottom above which a device for pulverizing the yeast is arranged. In order that the current of air may come from all sides into the most efficient contact with
- 15 the particles of yeast, the apertures in the intermediate partition-bottom are formed in a special manner, and furthermore provisions are made that the finely divided particles of yeast are carried along with the current
- 20 of air, leaving the container and being conducted to a collector having compartments into which the particles of yeast of different size are deposited so that a sorting of the yeast is thereby obtained. The compartments of the collector are each provided with heating means, which may be independently regulated in order to finally dry the yeast deposited therein to the desired degree and to obviate condensing of
- 25 humidity.
- 30

In order that my invention may be properly understood, I annex two sheets of drawings in which the preferred embodiment of my apparatus is illustrated.

- 35 Fig. 1 is a diagrammatical vertical section through my improved drying device together with the collector. Fig. 2 is a plan of the intermediate partition bottom, consisting in essence of two superposed plates containing between themselves apertures for the passage of air. In sector I of this figure the lower plate is illustrated, the upper plate being removed. Sector II shows the upper plate alone and in sector
- 40
- 45 III the plates in super-position are illustrated. Figs. 3, 4 and 5 are vertical sections on the lines *a—a* and *b—b* and *c—c*, respectively of the sectors I, II and III. Fig. 6 is a vertical section on the broken line *d—d* of Fig. 2.
- 50

The container for the reception of the yeast to be dried consists of a receptacle or basin 2 rotatable on its middle axis and having ball-bearings 1; above this receptacle 55 there is arranged a fixed cover 3 hermetically sealing the receptacle by means of a liquid seal of known kind. Axially of the receptacle a tube 5 extends downwards into which discharges the conduit 6 for the air, which has a concentric groove 7 filled with a liquid in which the tube 5 is immersed in order to secure an air-tight seal. The fixed cover is provided with an outlet tube 8 passing to the collector 9. A pulverizing device is 60 rotatably mounted in the depending por-

tion of the fixed cover, and consists, in the illustrated example, of a plurality of cutter-blades 10 fixed to annular supports 11, 11 on the axis 12. These cutter-blades are arranged in a cylindrical surface and are 70 formed in a screw-like manner. The cover is further provided with scrapers or turners 13 extending from the lower side of the cover downwards to an intermediate partition bottom 15 mounted in the receptacle 2 75 and having vertical apertures 14. These scrapers plough and turn the yeast deposited on this bottom 15 when the receptacle is rotated.

The collector 9 consists of a plurality of 80 concentric shafts 16, 17, 18 enlarging conically on one end and discharging on the opposite ends into a series of compartments 19, 20, 21, respectively, each of which is provided with heating means, for example 85 with steam-serpentine 19^a, 20^a and 21^a, respectively. The shafts together with the compartments are included into a common casing 22. This casing which is provided with doors (not shown) for the removal of 90 the collected and dried yeast from the compartments 19, 20, 21 which are also provided with suitable doors (not shown), encloses also the upper conical ends of the shafts and is provided at such upper portion with 95 a heating device as indicated at 23 for preventing condensation. Baffle-plates 24, 25 are fixed on the upper wall of the exterior shaft and extends into the conical discharge ends of the other shafts. Air outlet ports 100 26 are arranged in the top plate of the casing, surmounted by a roof-like cover 27.

The operation of the device is as follows: The yeast to be dried is deposited through an opening (not shown) in the cover 3 on 105 the intermediate partition bottom 15 of the receptacle 2 which is then rotated by means of a shaft 28 and of a toothed wheel 29 mounted on this shaft and of a toothed-wheel 30 provided at the outer circumference 110 of the receptacle. The shaft 28 may be driven from any source of power. The shaft 28 simultaneously actuates, for example by means of the worm-gear 31, the shaft 12, rotatably mounted in the cover so 115 that the cutter-blades 10 fixed thereon are brought into rotation.

By means of the conduit 6 suitably pre-heated air is supplied and is passed through the apertures 14 and through openings existing between the superposed plates and comes then into contact with the yeast, thereby 120 drying the same.

By the rotation of the receptacle 2 and of the intermediate partition bottom 15 the 125 yeast deposited thereon is partly lifted and turned by the fixed scrapers 13, the end of which may have the form of rakes; simultaneously the yeast is gradually cut into smaller and smaller particles. The cutters 130

also act as turning and distributing devices by partly turning, lifting and distributing the yeast.

The air flows out through the conduit 8 to the collector 9 and carries with it such small particles of yeast, the drying and pulverizing of which has taken place to such an extent as to allow their being swept away by the current of air.

10 The particles of yeast carried away by the current of air are deposited for the most part in the compartment 19, part of the yeast, namely the lighter particles, is lifted by the current between the walls of the 15 shafts 16 and 17 (as indicated in Fig. 1 by arrows), is brought after passing the baffle-plates 24 into the space between shaft 17 and 18 and fall down into the compartment 20; the still lighter particles are again lifted by 20 the current and are finally deposited after passing the baffle-plate 25 into the compartment 21.

On account of the repeated change of the direction of the outflowing air caused by the 25 baffle-plates, the particles of yeast carried along with the air are separated in their totality from the air so that practically air without any yeast particles leaves the casing 22 through the opening 26.

30 The collector therefore acts as a device for separating the smallest dust-like particles of yeast from the current of air, so that losses are obviated. In order to free the walls of the shafts from any particles 35 of yeast adhering thereto and to collect them in the respective compartment, a vibrator is provided consisting of a stem 32 actuated by a cam 33 on the shaft 28 so as to be pushed against the wall of the outer shaft 40 16. A tension spring brings the stem back to its original position. By the slight tapping of this stem onto the wall any particles of yeast adhering to the walls of the shafts and to the baffle-plates are caused to 45 fall down. Each compartment 19, 20, 21 is independently heatable, as already stated, for example by means of steam-pipes or the like for a further drying treatment of the yeast. In order to obtain a good uniform

50 drying of the yeast it is necessary that the air comes into an intimate contact with all sides of the yeast particles. On account of the humidity the yeast tends to form lumps and to choke the openings for the passage 55 of air thereby preventing a uniform contact of the air with and an efficient drying of the yeast. According to the invention the uniform contact of air under a low pressure with the yeast is obtained by a special 60 shape of the intermediate partition bottom on which the yeast to be dried is deposited.

This bottom essentially consists of two superposed plates 35, 37, which have there- 65 between a series of channels 39 in the shape of dies, each series of channels being pro-

vided in a sector of the plane, the lower and upper plate being divided into a series of sectors. The surface of the lower plate consists in each sector of a series of bevelled or tapered planes 36, which are oblique and 70 of which every two adjacent planes form together roof-like surfaces. In each sector part of the upper plate 37 is removed so that an opening 40 is created. One edge of the remaining part of the upper plate is 75 zigzag-lined and preferably provided with teeth 38, whereas the other radial edge is unbroken.

The form of the inclined or bevelled planes 36 of the lower plate 35 is diagrammatically shown in sector I of Fig. 2, in which the section-lines of horizontal planes with the bevelled planes 36 of the lower plate are indicated by the zigzag lines $f-f$, 80 $g-g$, $h-h$.

The lower sides of the points of the teeth 38 rest on the lower plate 35 along lines of the same level, i. e. along zigzag lines. On account of the bevel of the planes of the lower plate the interstices 39 (Fig. 5) between these two plates, (the lower 35 and the upper plate 37), have the shape of a die lying in the direction of concentric cycles. The discharge ends of these die-like channels 39 are divided by the teeth 38 of the upper- 95 plate 37 into a plurality of separate discharge openings. The current of air supplied by the conduit 6 passes through the vertical ports 13 of the lower plate and enters the channels 39 between the lower and upper plate, discharging in the yeast deposited on the upper-plate. On account of the zigzag-form of the discharge end of the channels 39 a relatively large cross-section of discharge is secured and the current is 100 subdivided by the teeth 38 into single streams blowing in different directions. For further subdividing and distributing the current of air the upper-plate 37 may be provided on its lower side with ribs resting 105 on the upper surface of the lower plate so that a series of channels or compartments of different directions are formed through which the air passes.

In order to prevent chocking of the air 115 inlets the die-like channels are situated in the direction of concentric cycles and pass obliquely from below to above, thereby enabling removal of the yeast from the discharge openings when the yeast is ploughed 120 by the scrapers on rotating the receptacle 2.

To prevent escape of air between the edges of the rotating receptacle and the fixed cover the latter is provided with an annular plate 125 42 the lower edge of which extends into a groove 41 of the receptacle 2, which groove is filled with liquid. By these means any loss of yeast is obviated.

A branch 43 of the air conduit 6 supplies 130

air into the annular space between the plate 42 and the sides of the receptacle and of the cover so that the same air pressure is created therein, thereby assisting the seal 5 formed by the liquid.

What I claim as my invention and desire to secure by Letters Patent is:

1. In the process of drying yeast, the steps which comprise simultaneously subjecting 10 coarsely subdivided solid yeast masses to the action of a drying current of an innocuous gas and to such a pulverizing action that the particles of pulverized yeast are eventually carried from the pulverization 15 zone by the said drying gas current, and, thereafter, effecting separation of the yeast from the gas current.

2. In the process of drying yeast, the steps which comprise simultaneously subjecting 20 coarsely subdivided solid yeast masses to the action of a drying current of air and to such a pulverizing action as to render the yeast susceptible of conveyance from the pulverization zone by the action 25 of said air current, and, thereafter, effecting separation of the yeast from the air current.

3. In the process of drying yeast, the steps which comprise treating coarsely subdivided 30 solid yeast masses with a drying current of an innocuous gas while the yeast is being reduced to such a state of subdivision that it is eventually taken up by the gas current, conducting the said gas current and the

yeast carried thereby to a settling zone and 35 permitting separation of the yeast from the gas current while further subjecting the yeast to temperature conditions which will effect additional drying.

4. In the process of drying yeast, the steps 40 which comprise treating coarsely subdivided solid yeast masses with a drying current of air while the yeast is being reduced to such a state of subdivision that it is eventually taken up by the air current, conducting the 45 said air current and the yeast carried thereby to a settling zone and permitting separation of the yeast from the air current while further subjecting the yeast to temperature conditions which will effect additional 50 drying.

5. In the process of drying yeast, the steps which comprise simultaneously subjecting coarsely subdivided yeast masses to the action of a drying current of an innocuous 55 gas and to such a pulverizing action that the particles of pulverized yeast are carried from the pulverization zone by the gas current, separating the yeast from the gas current and, during the entire process, maintaining the yeast and gas current at such a low temperature as not to destroy the 60 vitality of the yeast.

DR. ERWIN KLEIN.
